UNITED STATES PATENT OFFICE.

FREDERICK LINDLEY HUNT SIMS, OF WESTON, CANADA.

ACETYLENE-GAS GENERATOR.

SPECIFICATION forming part of Letters Patent No. 782,995, dated February 21, 1905.

Application filed April 29, 1902. Serial No. 105,242.

To all whom it may concern:

Be it known that I, FREDERICK LINDLEY HUNT SIMS, mechanical engineer, of the village of Weston, in the county of York, Province of Ontario, Canada, have invented certain new and useful Improvements in Machines for Generating Acetylene from Carbid of Calcium, of which the following is a specification.

My invention relates to improvements in machines for generating acetylene from carbid of calcium of that class where preferably granulated carbid is fed into a large body of water. It has for its objects:

First. The doing away with the expense and danger of gasometers or storage-tanks for the gas, leaving practically no gas in the system except what is in the service-pipes and yet maintaining a practically uniform pressure at the burners and throughout the system.

Second. The reduction of the vapor of generation to a minimum.

Third. The perfect drying of the gas before it enters the service-pipes and the accomplishing of this without any special washers, purifiers, or similar parts, this object being attained by the special arrangement of parts having as their primary object a different function.

Fourth. To overcome the clogging at the valve-aperture whether above or below the orifice through which carbid drops into the generating-chamber through the "slacking" of carbid about the same or the formation of plug-lumps on connecting-rods, which has hitherto been the most vexatious hindrance to the success of machines of this class.

Fifth. To provide a machine absolutely safe and that can be looked after by persons of the lowest intelligence and safely recharged while in operation, though not having a storage-tank or gasometer. Most machines hitherto represented as rechargeable during operation are not really so, but simply have a storage from which lights are supplied while the operation of the machine proper is suspended to allow of recharging. My intention, however, has been to provide a machine that suspends none of its normal functions while being recharged and that hence shall be simple and free from danger.

Sixth. To provide a simple mechanical construction strong, durable, and safe, to reduce the size and weight in regard to capacity to a minimum, and to increase the life of the machine.

55

Seventh. Incidentally to make many minor improvements that will appear to any one familiar with the art in perusing the description now to follow.

Figure 1 of the drawings is an axial section 60 of the machine, except the tubular feed-valve and shaker-bar and its chain, which are shown in full form, at right angles to the arms of the tubular feed-valve. Fig. 2 is an axial section of the lower part of the barrel of the machine, 65 showing the tubular feed-valve in cross-section, and is therefore a section at ninety degrees from the line of section in Fig. 1 and on the same scale. Fig. 3 is an enlarged detail of the parts at the top of the machine. 70 Fig. 4 is a plan of part of Fig. 3, and Figs. 5 and 6 a detail of the key used in opening the machine to recharge.

In the drawings like letters of reference indicate corresponding parts in the different 75 figures.

It will be seen at once that the machine presents four main divisions—namely, the tank A, Fig. 1, the generating-chamber B, shaped like a diving-bell, preferably larger 80 below than above and having in its conical roof (the lower cone of the hour-glass-shaped casting G, Figs. 1 and 2) an aperture leading into the carbid-containing or governor chamber J, as also the two pipes g g, Fig. 2, the carbid-containing or governor chamber J having its top formed by the bottom of the carbid-reservoir C and the carbid-reservoir C having preferably a funnel-shaped bottom with an aperture communicating with the governor- 85 chamber J at its lowest point. There is also in large machines the water-jacket I, Figs. 1 and 2, a triangular annular chamber formed by the outside of the hour-glass-shaped casting G and the inner side of the barrel B'; but 90 as the lower part of the hour-glass-shaped casting in small machines is omitted, leaving a mere cone or funnel to form the bottom of the governor-chamber J, the chamber or wa- 95 ter-jacket I is not present in all my machines 100

and is therefore not a main or essential division.

Now, beginning at the top of the machine, for the purpose of enabling the carbid-reservoir C to be easily recharged with carbid from time to time, as desired, I provide the cast-iron finial C', Figs. 1 and 3, with its ordinary threaded neck, washer-seat, and aperture. On this is screwed the gland or collar c, plan of which is shown in Fig. 4, provided at the top with a raised boss in which are two indentations with rounded or slanting edges c' c', Figs. 3 and 4. Through the center of the gland c is bored and tapped the hole c², through which is screwed the tail of the bolt-shaped box-wrench D, Figs. 1 and 3, provided on its upper head with indentations d², similar to the indentations c' of the gland c, not running quite through the depth of the head, but ending in a shroud or web d⁵ to prevent a key or wrench being slipped down past the head of the box-wrench D to engage the gland or collar c. The screw-thread d of the tail of the box-wrench D is made to fit very tightly in the tapped hole c² of the gland c, and when the box-wrench D is screwed down tight on the collar c a gas-tight joint is insured by the washer d³, whose plan is shown by the dotted circles in Fig. 4. To avoid interference with the key K, Figs. 5 and 6, this washer does not pass over the indentations c' c'. The aperture d⁴ of the box-wrench D is preferably square-sectioned and is adapted to fit snugly over the square-headed upper end of the check-valve spindle D'. (See Figs. 1 and 3.) The key K, Figs. 5 and 6, has its two teeth k' k' adapted to fit indifferently into the indentations c' c' or d' d' and is further provided with the shroud k.

Before describing the operation of the parts K, D, and c it will be better to describe also the shoe E, preferably of galvanized cast-iron soldered fast to the bottom of the funnel forming the bottom of the carbid-reservoir C, about the aperture there communicating with the governor-chamber J. This shoe E, Fig. 1, has two or more legs above, entering within the carbid-reservoir C and uniting to form the nut e, through which the check-valve spindle D' screws up and down. At its lower aperture the shoe E has a valve-seat turned to a knife-edge e³, into which the conical valve D² is adapted to fit. This valve is rigidly keyed with a gas-tight joint to the check-valve spindle D' at its lower end below the nut e and within the governor-chamber J and is adapted as it rises, turning, to grind away any lumps of carbid on its side, making what I believe to be the only feasible durable practically gas-tight granulated-carbid valve. The conical valve D² is preferably chilled cast-iron finished true on its conical face by grinding, and the knife-edge on the shoe E is preferably case-hardened. It may be here mentioned that the shoe E has also a side extension pro-

vided with a lug e', with a threaded aperture corresponding to an aperture in the side of the barrel B'. Into this lug the service-pipe e² is firmly screwed, the lug thus providing a solid point of affixture for the service-pipe and at the same time bracing the shoe E against being twisted off the bottom of the carbid-reservoir C when the valve D² is screwed firmly up to its seat.

To open the carbid-reservoir to the outer air for recharging, the key K is fitted, with its key k', into the indentations d² of the head of the box-wrench D and the box-wrench unscrewed until it jams tight, which it will do when the valve-spindle D', turning with the box-wrench, (owing to its upper square end d' being within the square aperture d of the box-wrench D,) has unscrewed through the nut e at its lower end far enough to bring the valve D² firmly up against the knife-edged valve-seat e³, closing the aperture at the bottom of the carbid-reservoir C, and so cutting the carbid-reservoir C off absolutely from communication with the rest of the machine. If an attempt be made to remove the key K from the head of the box-wrench D to unscrew with it the collar or gland c before the box-wrench D has been unscrewed enough to seat the valve D² and cut off communication between the carbid-reservoir and the rest of the machine, it will be found that it cannot be successfully accomplished, because the vertical height of the key K will prevent effective hold being taken of the gland or collar c until the head of the box-wrench D is unscrewed high enough to allow the body of the wrench K to be slipped in a horizontal plane between the under side of the head of the box-wrench D and the top of the boss on the gland or collar c. When this has been done and the shroud k of the key K fitted close up to the tail of the box-wrench, the key K can be readily pushed down, with its two teeth k' k' fitting one each into the two indentations c' c' of the gland or collar c. The shrouds d⁵ effectually prevent the key being slipped down the indentations of the head into engagement with the indentations of the boss. If an attempt be made to use the key K on the collar or gland c as a cant-hook with only one of its teeth k' fitting in one indentation c' of the gland or collar c and the other resting on the periphery it will take no hold, but slip immediately, owing to the curved or slanting edges of the indentations c' c', Fig. 4; but when the box-wrench D is so unscrewed high enough to allow the key to take proper hold of the gland, as above, the valve D² is set firmly on its seat e³, the thickness of the key K being proportioned exactly to the allowed rise of the valve D². Hence it is impossible to get at the gland or collar c, the unscrewing of which opens the carbid-reservoir to the outer air for recharging, until communication between the carbid-reservoir and the rest of the apparatus has been ab-

solutely cut off. The box-wrench D having been unscrewed till it jams, as above, the key K is inserted, with its teeth $h' h'$ inserted one each into the indentations $c' c'$ of the gland c, as above, and the gland unscrewed, when, as the box-wrench will of course not unscrew any more, since it is already jammed, the collar or gland c screws upon the tail d' of the box-wrench D, putting the wrench K "in chancery" by catching it between the top of the gland c and the under side of the head of the box-wrench D. It can only be got out (unless some other tool be used) by screwing the collar or gland c in place again, and hence there is no human probability that the key K will be used to screw down the box-wrench again until the collar or gland c is first screwed down. It could only happen through bad faith—not through inattention or carelessness. This prevents communication being reestablished between the carbid-reservoir C and the rest of the apparatus until the aperture leading to the outer air through the finial C' has been closed by screwing on the gland or collar c, which makes a gas-tight joint by means of the washer c^3 .

When it is desired to close the carbid-reservoir after recharging, the box-wrench, gland, and key are lifted together by the handles of the key and the box-wrench D fitted over the valve-spindle D', the aperture d^4 engaging the square end d' , as above. The gland or collar c is now screwed down tight on the washer c^3 , and, the box-wrench remaining stationary meantime, owing to the friction grip of the valve D' on the knife-edged valve-seat c^2 , the collar or gland c screws down about the tail d of the box-wrench just as before it screwed up, and thus leaves room to free the key K and fit it in turn to the indentations $d^2 d^3$ of the box-wrench D and in turn screw it down tight on the washer d^3 , thus closing the carbid-reservoir and putting the parts in as they were before removal. It will thus be seen that by the means shown at the top of Fig. 1 and in Figs. 3, 4, 5, and 6 although the carbid-reservoir C may be opened and closed at will it cannot be done without closing or cutting off communication between the carbid-reservoir and the rest of the apparatus before the carbid-reservoir can be opened to recharge or without reestablishing such communication between the carbid-reservoir and the rest of the apparatus before the carbid-reservoir is finally closed after recharging. It also follows that the carbid-reservoir must necessarily be closed against the escape of gas by the first part of the operation of closing (rendered absolutely imperative by the shape and arrangement of the parts) before the second part of such operation of closing reestablishes such communication, as aforesaid. The reason for this being so specially provided will appear in the de-

scription of the operation of the machine to 65 follow.

Coming next to the carbid-holding or governor chamber J, it will be noted that its bottom is funnel-shaped, the funnel having a main aperture at its apex (which, the funnel being inverted, is its lowest part) stopped normally by the tubular feed-valve H, preferably somewhat flaring or trumpet-shaped, though it may be a mere piece of tube provided with two opposite arms $h' h'$, Figs. 1 and 2, making the tubular feed-valve T-shaped, and that to the ends of the arms of this T-shaped tubular feed-valve connecting-rods $h^2 h^2$, Figs. 1 and 2, are firmly attached, being preferably screwed into same. These connecting-rods connect with the float F, as will be shown in describing the generating-chamber B. Meantime it will be noted that they pass through two minor apertures in the bottom of the governor-chamber J, these apertures being the upper ends of the pipes or tube-channels $g g$, Figs. 1 and 2, and that an arched cover of peculiar shape, having notably the formation of the lower part of its sides arch-shaped with the crown of the arch in the middle, (see Fig. 2, h; also Fig. 1, h,) covers both the T-shaped tubular feed-valve, the rods, and the holes or upper ends of the pipes $g g$, preventing carbid dropping through to the generating-chamber B or interfering in any way by its weight with the free action of the valve. The cover h also prevents carbid dropping through the tubular valve. The only other feature of the governor-chamber J is the service-pipe c^2 at its upper part, from which gas-service is taken. In connection with the governor-chamber J may be described the water-jacket space I, with the aperture or apertures i leading into same. It is formed, preferably, by soldering the hour-glass-shaped casting G above and below in the lower part of the barrel B' with water and gas tight joints, thus isolating an annular chamber of triangular section I, through which the pipes $g g$ pass, (forming a way for the connecting-rods $h^2 h^2$.) This chamber may be filled with water through the aperture or apertures i to form a condenser or water-jacket, particularly in large machines carrying an extra-heavy load. Thirdly, in the generating-chamber B will be noticed the annular float F, (partly shown in Fig. 2 and dotted all round in Fig. 1,) where it will be seen that it is normally partially immersed in the water within the generating-chamber, the water reaching just below the line of flotation—namely, the dotted line in Fig. 2—when at rest and the machine is out of use. On the under side of this float F on the same diameter, but at opposite sides of the circular opening through it, are the lugs $f f$, Figs. 1 and 2, riveted, preferably, thereto and having holes through which the connecting-rods $h^2 h^2$ have their lower threaded ends

passed, with nuts above and below same to make a strong attachment of the rods to the lugs, and so to the float F. At the same time this connection permits of the ready removal 5 of the rods to prevent damage to the float F in shipping, &c., and also to provide a ready and simple means of adjustment or leveling.

In very large machines the valve H has three or more arms, and there are three or more connecting-rods and three or more lugs f f, attached to the float F, or three floats are used, one to each rod. As this machine never over-generates, I show no blow-off, as it is useless except where necessary to comply with underwriting rules; but if used it may, of course, be set to blow off at any desired head. The generating-chamber has no bottom, but is held rigidly immersed in the water in the tank A by the braces b b, riveted or bolted to the sides 10 of the barrel B' and the annular top of the generating-chamber B, and having holes in their outer extremities through which bolts secure them to the angle-irons a', attached to the sides of the tank A. Three or more braces, &c., are 15 used, according to size of machine. These braces and their attachments form a simple means of securing the dome of the apparatus in the water-tank and permit its ready removal for shipping, &c. They also strengthen the 20 dome and stiffen it materially. Their horizontal parts are normally about one inch below the water-level of the tank A, as shown in Fig. 1. Lastly, the tank A has several novel features. It is provided with a sloping bottom 25 of preferably shallow V-shaped section, (one sloping side of the V is shown in perspective in Fig. 1, the section-line of the drawings being along the bottom of the V,) and at the lowest point in the side of the tank A is a 30 "perfection faucet" or suitable draw-off cock A² for drawing off the calcium hydrate residuum formed during the action of the machine. Not quite half-way to the top of the tank directly above the faucet A² is a special angle-iron bearing a³, with a hole in its 35 horizontal slide through which the perpendicular part of the shaker-bar A³ passes, the angle-iron a³ being riveted to the side of the tank A and the shaker-bar having a boss 40 upon its perpendicular part adapted to rest on the top of the angle-iron a³ in its normal position to keep the shaker-bar at its proper elevation when at rest. Near the top is a guide-staple a², (half of which only appears in Fig. 45 1,) riveted also to the side of the tank A and long enough to allow the shaker-bar to be pushed in and out in a radial direction. The shaker-bar at the upper end is formed into the usual handle, but at the end of its lower 50 55 L-shaped arm is formed an eye to which is secured a chain a equal in length to the side of the inscribed square on the bottom of the tank A and with its end remote from the shaker-bar attached to a second staple a', riveted to the side of the tank A. This chain a

threshes to and fro in the lower part of the tank A when the handle of the shaker-bar is agitated in a horizontal plane. By raising the handle of the shaker-bar A³ into different planes it will be readily seen that its lower 70 end, in combination with the chain a and its accompanying parts, provides a simple, durable, and effectual means of thoroughly admixing the water and the calcium hydrate or "sludge" whenever it is desired to draw off 75 the latter through the faucet A². To prevent the faucet choking meantime, (the great objection of all users of the carbid to water process,) I provide the preferably conical plug a⁵ at the lower angle of the shaker-bar. When 80 sludge has been drawn off, the handle of the shaker-bar A³ is always pushed in and down toward the center of the machine, and the angle-iron a³ acting as a fulcrum and the boss on the bar acting as a gage the conical plug a⁵ closes 85 the inner aperture of the faucet A² and renders clogging or plugging impossible.

Having now described all the parts of the machine, I shall briefly sketch its operation. The service-pipe e² being connected to the system with burners where gas is to be used, the gas-cocks are turned on, the carbid-reservoir C opened, as described, thereby closing the aperture within at its lowest point by the valve D² and the carbid put in with a funnel, 90 granulated carbid being used, pea or rice size. The carbid-reservoir is then closed, thereby throwing open the aperture below, and part of the carbid falls immediately into the governor-chamber J, leaving a space at 95 the top of the carbid-reservoir C, as shown in Fig. 1, in which, to make the drawing clear, all the carbid in C and J is shown in dotted section and treated as though transparent. In falling into the governor-chamber J it will be observed that an annular space of triangular section is left at the top of J, from which the service-pipe leads. A small space is also left within the carbid 100 itself in the governor-chamber J under the valve D², the carbid falling at its angle of rest, which is slightly over forty-three degrees, for which reason the funnel-bottoms of C and J are both made fifty-three degrees, being by experiment the best angle to insure feed when bottom apertures are open, and yet not a rush-feed. There is a third empty space in the governor-chamber J under the collector or cover h and within the same. The collector or cover h has its ends fitted practically gas-tight against the bottom and sides of the governor-chamber J, so that any gas collecting under it must first fill it and then escape, as hereinafter shown. The carbid is prevented 105 from falling into the generating-chamber B and tank A by the tubular feed-valve H and cover h, as before described. Water is now poured into the tank till it reaches a height above the top of the generating-chamber B, when it will begin to force out the air 110

from the generating-chamber B through the tubular feed-valve H, and the pipes g g, and the carbid j to the service-pipe, and so through the burners, until the water rising 5 within the generating-chamber B eventually passes the line of flotation, (see dotted line Fig. 2,) being constantly replenished in the tank A in starting-machine to maintain the level about one inch above the top of the generating-chamber B outside in the tank A. The float F now lifts very slightly by means of the rods h² and the arms h', raising slightly the tubular feed-valve H, when, owing to the scientific angle at which, as above described, 15 the funnel-bottom of the governor-chamber J has been designed carbid feeds through the smallest possible opening, instead of through an opening larger than the smallest possible opening, as would be the case were 20 the sides of the bottom of J say forty-five degrees. The carbid comes also without a rush, and hence the smallest practicable amount of carbid is dropped through the aperture of communication between the governor-chamber J and the generating-chamber B into the water in the inner circle of the annular float F. As nothing whatever lies in the way of the drop, nothing can foul. When the carbid reaches 25 the water, gas instantly forms and rushes up 30 through the tubular valve H in the direction of the straight arrow in Fig. 2 and also pushes down the water below the line of flotation, when the float falls, pulling down the tubular feed-valve H and cutting off the carbid-feed. The 35 water starts to rise again, no more now being added to the tank A, and so the operation is repeated till the air is expelled and gas comes that can be lighted at the burners. Now as the gas is formed from the smallest possible 40 amount of carbid that can be dropped at one time, as above, it is evident that the smallest possible amount of vapor or steam is evolved in its generation, the machine being designed to feed "early and often," and so comparatively 45 dry gas starts at the outset on its journey through the tubular feed-valve H and the pipes g g to mass or collect under the cover or collector h. This becoming full, the gas escapes at the highest point of its arched 50 under sides, as shown by the curved arrows, Fig. 2, where any slight moisture in it is taken up by the carbid, as shown by the slightly heavier shade, at the heads of the curved arrows, Fig. 2. Where the water-jacket I is used, moisture is also condensed on the under cone of the casting G and in the pipes g g, and when it amounts to enough to form a drop trickles down into the generating-chamber B again. This only occurs when a 55 very large machine is running a very heavy load. It will be seen that by the arrangement described no gas of any kind attacks the carbid immediately about the seat of the tubular feed-valve H, and when the slightly 60 damped or attacked carbid, shown at the heads

of the curved arrows, works down to the feed-aperture it is dried to quicklime-dust and feeds as readily as the crystals. Hence my valve never clogs. Further, after the gas escapes from the crown of the arched under 70 sides of the collector h it follows the line of least resistance straight up through the carbid to the little space under the valve D², as shown by the three arrows in Fig. 2, and so out to the space in the governor-chamber J above 75 the carbid j in the same, and thence directly into the service-pipe. Right here occurs the most novel feature of this invention—namely, that by the means described the gas is compelled to pass right through the upper two 80 thirds of the middle of the carbid j in the governor-chamber J without attacking it about its sides or the feed-valve seat, where it would stay sticky, and clog sooner or later, and by this means I am enabled to use the 85 carbid j in the governor-chamber J as a friction-check or interstitial conduit to withdraw the gas and take off the varying pressures arising from instantaneous generation and slight changes of water-level in the tank A 90 and the generating-chamber B, producing a practically uniform pressure at the top of the governor-chamber J, and so, also, in the service-pipe, without the use of a gasometer or any form of governor other than the carbid 95 itself. This advantage is enhanced by the fact that in the reservoir C, I have a supply of carbid ample to replenish the governor-chamber J with clean fresh carbid unattacked by any moisture as J empties into the generating-chamber B by the action of the float and feed valve and also by the fact that the carbid j in the governor-chamber J, while so withdrawing the gas and equalizing the pressure as above, serves as the best-known 100 siccatice to dry, purify, and, by taking up sensible heat, refrigerate the gas.

The operation of the means for stirring up the sludge and running same off through the faucet A² for keeping the faucet clean when in use, &c., has been so clearly implied in describing the shaker-bar A³, &c., that nothing more is needed in explanation than to say that water run off is of course replaced in the tank A and that sludge is run off whenever on 110 shaking the shaker-bar A³ it is found that it moves stiffly, indicating an accumulation of sludge in the tank.

After the machine has supplied gas until the carbid-reservoir C is empty (which is ascertained by tapping its outer lower conical side) it becomes necessary to recharge same. The operations of opening and closing the aperture in the finial C' at the top have been already fully described, so that here it is only 120 necessary to explain why such care has been taken to provide means involving the necessary closing of the aperture at the bottom of the carbid-reservoir C (in the shoe E) before the second part of the operation of opening 125

130

the aperture at the top of the carbid-reservoir C (in the finial C') can be performed, and, conversely, that the said aperture at the top of the carbid-reservoir C (in the finial C') shall necessarily be closed against the escape of gas (by the first part of such operation of closing) before the second part of such operation of closing at the same time involves or necessitates the opening of the aperture at the bottom of the carbid-reservoir C in the shoe E. When it is remembered that all the gas in the apparatus above water in the generating-chamber B is always under pressure while the water-level in the tank A is higher than the water-level in the generating-chamber B, it becomes evident that if the carbid-reservoir C is put into communication with the outer air while it is at the same time in communication with the governor-chamber J, and so with the generating-chamber B, gas will instantly rush out into the outer air at a rate equal to the capacity of the passage so opened and continue to do so until all the carbid in the machine is exhausted. This would cause heat, dirt, disagreeable odors, and possibly accident, besides damaging the apparatus. Hence the greatest care has been taken by me to provide means practically infallible to insure the absolute isolation of the carbid-reservoir C from the rest of the apparatus before it can be opened to the outer air to recharge, and, further, to insure the practical cutting off of all communication between the carbid-reservoir and the outer air before it shall be possible in the operation of the parts provided to reestablish communication between the carbid-reservoir C and the rest of the machine.

What I claim as my invention is—

1. In apparatus for generating acetylene, a carbid-chamber having an aperture in its casting through which it may be charged, and an aperture at the bottom, through which it may be emptied, in combination with mechanism for opening and closing the apertures; and a removable key for operating said mechanism, the key and said mechanism being so constructed that the key cannot be engaged with the mechanism used to open one aperture until it has been used to close the other, substantially as described.

2. In apparatus for generating acetylene, a carbid-chamber having an aperture in its casting through which it may be charged and an aperture at the bottom through which it may be emptied; a valve for the lower aperture; a threaded valve-stem secured thereto and having its upper end squared; a stationary nut through which the said spindle is screwed; a gland or collar provided with a central threaded opening and in place at the upper aperture; a box-wrench screwed into the said opening and adapted to detachably engage the squared upper end of the valve-spindle; and a key adapted to engage the gland and box-wrench, the key-gland and box-wrench being

so shaped that the key cannot be engaged with the gland until it has been engaged with the box-wrench and the valve closed, substantially as described.

3. In apparatus for generating acetylene, a carbid-chamber having an aperture in its casting through which it may be charged and an aperture at the bottom through which it may be emptied; a valve for the lower aperture; a threaded valve-stem secured thereto and having its upper end squared; a stationary nut through which the said spindle is screwed; a gland or collar provided with a central threaded opening and in place at the upper aperture; a box-wrench screwed into the said opening and adapted to detachably engage the squared upper end of the valve-spindle; and a key adapted to engage the gland and box-wrench, the key-gland and box-wrench being so shaped that the key cannot be engaged with the gland until it has been engaged with the box-wrench and the valve closed, and so that after being used to unscrew the gland it cannot be removed for use on the box-wrench till the gland is again screwed in place, substantially as described.

4. In apparatus for generating acetylene, a carbid-chamber having an aperture in its casting through which it may be charged, and an aperture at the bottom through which it may be emptied; a valve for the lower aperture; a threaded valve-stem secured thereto and having its upper end squared; a stationary nut through which the said stem is screwed; a threaded finial surrounding the upper aperture; a gland or collar screwed on the said finial; a box-wrench screwed into the said gland and adapted to detachably engage the squared upper end of the valve-spindle; a boss formed on the gland and provided with two vertical indentations; a head on the box-wrench provided with similar indentations; and a key shaped to engage the said indentations of either the head or boss, substantially as described.

5. In apparatus for generating acetylene, a carbid-chamber having an aperture in its casting through which it may be charged, and an aperture at the bottom through which it may be emptied; a valve for the lower aperture; a threaded valve-stem secured thereto and having its upper end squared; a stationary nut through which said stem is screwed; a threaded finial surrounding the upper aperture; a gland or collar screwed on the said finial; a box-wrench screwed into the said gland and adapted to detachably engage the squared upper end of the valve-spindle; a boss formed on the gland and provided with two vertical indentations; a head on the box-wrench provided with similar indentations running only partially through the depth of the head; and a key shaped to engage the said indentations of either the head or boss, the parts being so proportioned that sufficient room cannot be

had between the boss and head for the wrench to be slipped in between the two for engagement with the boss until the valve is entirely closed, substantially as described.

5 6. In apparatus for generating acetylene, a carbid-chamber having an aperture in its casting through which it may be charged, and an aperture at the bottom through which it may be emptied; a valve for the lower aperture; 10 a threaded valve-stem secured thereto and having its upper end squared; a stationary nut through which the said stem is screwed; a threaded finial surrounding the upper aperture; a gland or collar screwed on the said finial; a box - wrench screwed into the said gland and adapted to detachably engage the squared upper end of the valve-spindle; a boss formed on the gland and provided with vertical indentations running only partially 15 through the depth of the head; and a key shaped to engage the said indentations of either the head or boss, and provided with a web or shroud forming a semi-annular flange extending inwardly at one side of the key, the 20 parts of the head, boss, and key being so shaped and proportioned that sufficient room cannot be had between the boss and head for the wrench to be slipped in between the two for engagement with the boss until the valve 25 is entirely closed, substantially as described.

7. In apparatus for generating acetylene, a carbid-chamber having an aperture in its casting through which it may be charged, and an aperture at the bottom through which it may be emptied; a valve for the lower aperture; 30 a threaded valve-stem secured thereto and having its upper end squared; a stationary nut through which the said stem is screwed; a threaded finial surrounding the upper aperture; a gland or collar screwed on the said finial; a box-wrench screwed into the said gland and adapted to detachably engage the squared upper end of the valve-spindle; a boss formed on the gland and provided with two vertical 35 indentations with slanting walls; a head on the box-wrench provided with similar indentations running only partially through the depth of the head; and a key shaped to engage the said indentations of either the head or boss, the 40 parts being so proportioned that sufficient room cannot be had between the boss and head for the wrench to be slipped in between the two for engagement with the boss until the valve 45 is entirely closed, substantially as described.

5. In apparatus for generating acetylene, the combination of a water-tank; a diving-bell generating-chamber secured within the said tank; a carbid-containing chamber having a horizontal opening at the bottom communicating with the interior of the generating-chamber; a vertically-movable valve governing the said opening and located within the carbid-containing chamber; a float adapted to rise and fall with the water-level in the generating-chamber; and a connection between the float and the valve, the connection being arranged so as to be out of line with the aforesaid valve-controlled opening and not passing through the same, the carbid-chamber having a special opening for the passage of the said connection; substantially as described.

6. In apparatus for generating acetylene, the combination of a water-tank; a diving-bell generating-chamber secured within the said tank; a carbid-containing chamber having a horizontal opening at the bottom communicating with the interior of the generating-chamber; a vertically-movable open-ended tubular valve governing the said opening and located within the carbid-containing chamber; a float adapted to rise and fall with the water-level in the generating-chamber; and a connection between the float and the valve, the connection being arranged so as to be out of line with the aforesaid valve-controlled opening and not passing through the same, the carbid-chamber having a special opening for the passage of the said connection; substantially as described.

7. In apparatus for generating acetylene, the combination of a water-tank; a diving-bell generating-chamber secured within the said tank; a carbid-containing chamber having a horizontal opening at the bottom communicating with the interior of the generating-chamber; a vertically-movable open-ended tubular valve governing the said opening and located within the carbid-containing chamber; a float adapted to rise and fall with the water-level in the generating-chamber; and a connection between the float and the valve, the connection being arranged so as to be out of line with the aforesaid valve-controlled opening and not passing through the same, substantially as described.

8. In apparatus for generating acetylene, the combination of a water-tank; a diving-bell generating-chamber secured within the said tank; a carbid-containing chamber having a horizontal opening at the bottom communicating with the interior of the generating-chamber; a vertically-movable open-ended tubular valve governing the said opening and located within the carbid-containing chamber; a float adapted to rise and fall with the water-level in the generating-chamber; and a connection between the float and the valve, the connection being arranged so as to be out of line with the aforesaid valve-controlled opening and not passing through the same, substantially as described.

9. In apparatus for generating acetylene, the combination of a water-tank; a diving-bell generating-chamber rigidly secured within the said tank; a carbid-containing chamber having an opening communicating with the interior of the generating-chamber; a valve governing the said opening; a float adapted to rise and fall with the water-level in the generating-chamber; an operating connection between the float and valve passing through an aperture formed in the carbid-containing chamber; and a cover over the said opening adapted to prevent carbid falling into the opening and to conduct gas from the opening into the body of carbid, substantially as described.

10. In apparatus for generating acetylene, the combination of a water-tank; a diving-bell generating-chamber secured within the said tank; a carbid-containing chamber having a carbid-opening and one or more gas-openings formed therein communicating with the interior of the generating-chamber; a valve governing the carbid-opening; a float within the generating-chamber adapted to operate the said valve; and a cover over the said gas opening or openings adapted to prevent carbid falling into the said openings and to conduct gas from the openings into the body of the carbid, substantially as described.

11. In apparatus for generating acetylene, the combination of a water-tank; a diving-bell generating-chamber secured within the said tank; a carbid-containing chamber having a horizontal opening at the bottom communicating with the interior of the generating-chamber; a vertically-movable valve governing the said opening and located within the carbid-containing chamber; a float adapted to rise and fall with the water-level in the generating-chamber; and a connection between the float and the valve, the connection being arranged so as to be out of line with the aforesaid valve-controlled opening and not passing through the same, the carbid-chamber having a special opening for the passage of the said connection; substantially as described.

12. In apparatus for generating acetylene, the combination of a water-tank; a diving-bell generating-chamber secured within the said tank; a carbid-containing chamber having a

13. In apparatus for generating acetylene, the combination of a water-tank; a diving-bell generating-chamber secured within the said tank; a carbid-containing chamber having a carbid-opening and two gas-openings formed therein communicating with the interior of the generating-chamber; an open-ended tubular valve governing the carbid-opening and located within the carbid-chamber; an annular 10 float within the generating-chamber; connecting-rods secured to the float passing through the gas-openings and connected with the tubular valve inside the carbid-chamber; and an arched cover secured over the gas-openings 15 and the upper end of the valve to exclude carbid, gas-exits being provided at its sides below the level of the said openings and valve-top, substantially as described.

14. In apparatus for generating acetylene, the combination of a water-tank; a diving-bell generating-chamber secured within the said tank; a carbid-containing chamber having an opening communicating with the interior of the generating-chamber; an open-ended tubular valve governing the said opening and located within the carbid-chamber; an arched cover secured over the valve to exclude carbid and provided with a gas-exit below the level of the upper end of the said valve; and a 20 float within the generating-chamber adapted to operate the said valve, substantially as described.

15. In apparatus for generating acetylene, the combination of a water-tank; a diving-bell generating-chamber secured within the said tank; a carbid-containing chamber having an opening communicating with the interior of the generating-chamber; an open-ended tubular valve governing the said opening and located within the carbid-chamber; an arched cover secured over the valve to exclude carbid, and provided with central gas-exits at each side below the level of the upper end of the said valve so that gas passing through the 30 valve is conveyed into the central portions of the carbid in the carbid-chamber; a service-pipe communicating with the interior of the carbid-chamber above the carbid therein; and a float within the generating-chamber adapted to operate the said valve, substantially as described.

16. In apparatus for generating acetylene, a carbid-containing chamber having its sides formed by a barrel or cylinder, in combination with an hour-glass-shaped bottom forming with the barrel an annular triangular-sectioned water-jacket, a hole or holes being formed in the barrel communicating with the upper part of the water-jacket, substantially as described.

17. In apparatus for generating acetylene, a carbid-reservoir having an aperture in its lower end; a carbid-containing chamber with which the said aperture communicates, in combination with a casting forming a valve-seat

about the said opening, and provided with a lateral extension having a lug formed thereon having a threaded aperture therein; and a service-pipe passing through the side of the chamber and screwed into the said lug, substantially as described.

18. In apparatus for generating acetylene, a carbid-reservoir having an aperture in its lower end; a carbid-containing chamber with which the said aperture communicates, in combination with a casting forming a valve-seat 75 about the said opening, and provided with a lateral extension having a lug formed thereon; having a threaded aperture therein and secured to the side of the carbid-chamber; and a service-pipe passing through the side of the 80 chamber and screwed into the said lug, substantially as described.

19. In apparatus for generating acetylene, the combination of a water-tank in which calcium hydrate settles to the bottom; a faucet 85 or draw-off cock communicating by a suitable opening with the interior of the tank in the side close to the bottom; a plug adapted to close the said opening from the inside of the tank; and a vertically-movable bar suitably 90 guided and supported to the lower end of which the said plug is rigidly secured, substantially as described.

20. In apparatus for generating acetylene, the combination of a water-tank in which calcium hydrate settles to the bottom; a shaker-bar having a vertical portion vertically movable and also rotatable in bearings on the side of the tank and a laterally-extending lower portion lying on or adjacent to the bottom of 100 the tank; and a chain secured at one end to the end of the lower portion of the shaker-bar and the other to the tank at the side opposite the vertical part of the shaker-bar, substantially as described.

21. In apparatus for generating acetylene, the combination of a water-tank in which calcium hydrate settles to the bottom; a faucet or draw-off cock communicating by a suitable opening with the interior of the tank at the 110 bottom; a plug adapted to close the said opening from the inside of the tank; a vertical rod to which the said plug is secured; a central bearing for said rod so shaped that the rod may be rocked in and out in a radial direction in the said bearing and also moved vertically in the same; and a guide-staple for the upper part of the rod, substantially as described.

22. In apparatus for generating acetylene, the combination of a generating-chamber having water therein; a carbid-containing chamber having a carbid-opening and one or more gas-openings formed therein communicating with the interior of the generating-chamber; means controlled by the gas for controlling the said carbid-opening; and a cover extending over all the openings and so shaped as to

collect all the gas passing through the said openings and discharge it close to the axial line of the carbid, substantially as described.

23. In apparatus for generating acetylene, the combination of a water-tank; a diving-bell generating-chamber secured within the said tank; a carbid-containing chamber having a carbid-opening and one or more gas-openings formed therein communicating with the interior of the generating-chamber; a valve governing the carbid-opening; means for automatically operating the said valve controlled by the consumption of gas; and a cover over the said gas opening or openings adapted to prevent carbid falling into the said openings and to conduct gas from the openings into the body of the carbid, substantially as described.

24. In apparatus for generating acetylene, the combination of a water-tank; a diving-bell generating-chamber secured within the said tank; a carbid-containing chamber having a carbid-opening and two gas-openings formed therein communicating with the interior of the generating-chamber; an open-ended tubular valve governing the carbid-opening and located within the carbid-chamber; means for automatically operating the said valve controlled by the consumption of gas; connecting-rods secured to the float passing through the

gas-openings and connected with the tubular valve inside the carbid-chamber; and an arched cover secured over the gas-openings and the upper end of the valve to exclude carbid, gas-exits being provided at its sides below the level of the said openings and valve-top, substantially as described.

25. In apparatus for generating acetylene, the combination of a water-tank; a diving-bell generating-chamber secured within the said tank; a carbid-containing chamber having an opening communicating with the interior of the generating-chamber; a vertically-movable open-ended tubular valve governing the said opening and located within the carbid-containing chamber; a part adapted to rise and fall according to the consumption of gas; a connection between the said part and the valve, the connection being arranged out of line with the aforesaid valve-controlled opening; and a stationary cover over the upper end of the tubular valve to prevent carbid entering the same.

Toronto, April 23, 1902.

FREDERICK LINDLEY HUNT SIMS.
